(57) **CLAIM**

The ornamental design for an upper for a slipper, as shown and described.

DESCRIPTION

FIG. 1 is a top plan view of an upper for a slipper according to my new design;

FIG. 2 is a right side elevational view thereof;

FIG. 3 is a front elevational view thereof; and,

FIG. 4 is a left side elevational view thereof.

The bottom is plain and unornamented. The dashed lines are for environmental purposes only and form no part of this design.
